UNITED STATES PATENT OFFICE.

THEODORE H. OPPENHEIM AND BERNARD SELHORST, OF COLDWATER, OHIO, ASSIGNEES TO NEW IDEA SPREADER CO., OF COLDWATER, OHIO, A CORPORATION OF OHIO.

PNEUMATIC CONVEYER.

Original application filed November 29, 1924, Serial No. 753,007. Divided and this application filed April 13, 1926. Serial No. 101,796.

This application is a division of an application filed by us November 29, 1924, Serial No. 753,007, patented on March 22, 1927, No. 1,621,682, the present invention having for its object the provision of improved means for supporting the blower spout of a corn-husking machine.

In the annexed drawings:

Figures 1 and 2 are elevations of opposite sides of a corn-husking machine embodying the present invention, Fig. 1 showing the machine arranged for use and Fig. 2 showing it arranged for transportation or storage;

Fig. 3 is a plan view with the parts arranged as in Fig. 2;

Fig. 4 is a rear elevation.

The machine is mounted for travel upon wheels 1, and 2, a draft bar 5 being connected with the axle of the front wheels 1. The rear axle 9' is an inverted channel bar and side bars 9 are secured to the axles, these side bars constituting the chords of trusses which carry the major stresses of the main frame and include a rear inclined frame bar 12 on one side of the machine and a similar bar 16 on the opposite side of the machine.

At one side of the machine, the cutter head shaft carries a pulley 42 which is connected by a belt 43 with a pulley 44 on the blower shaft 45.

A blower and blast spout are provided at the rear end of the machine, as indicated at 68 and 69, respectively. The blower shaft is mounted in suitable bearings upon extension bars 70 and 71, the bar 71 being secured to and projecting rearwardly from the rear inclined frame bar 12, while the bar 70 is disposed laterally beyond the plane of the bar 16 and is connected by a coupling bar 72 with a brace 73 which is secured at its lower end upon the rear axle and extends upwardly and inwardly therefrom to the bar 16 to which it is secured. The bar 70 is further supported by posts 74 secured to and rising from the axle and the rear end of the side bar 9, and a post 75 rises from the side bar 9 at the opposite side of the machine to support the rear end of the bar 71. We thus provide a strong frame support for the blower and its shaft and also so brace the structure as to prevent one side of the frame creeping ahead of the other side and destroying the rigidity of the frame. The blower spout or blast pipe comprises a rigid section

75' which rises directly from the blower 68 55 and has a turntable 76 at its upper end. This turntable carries the jointed end portions of the spout whereby the spout is carried in a curvilinear manner, either forwardly or laterally or rearwardly, to said 60 jointed portions being connected with a rigid pipe section 77 of the usual length and provided at its end with a collar or band 78 having a flange 79 and equipped with an eye 80. A second straight section 81 is likewise provided with a band 82 having a flange 83. When the machine is in use, the flanges 79 and 83 are bolted together so as to form a tight joint, with the sections in alinement, so that the chaff and other waste matter may 70 be delivered at a point distant from the machine. The section 81 is provided at its delivery end with a deflecting hood 84 whereby the chaff and other material flowing through the spout will be directed downwardly to the ground. The spout and blower are, of course, located at one side of the machine, and to prevent warping of the machine through the vibration of the parts in operation, we provide a brace 85 which 80 is secured at one end to the turntable 76 and is shown as secured at its opposite end to the frame bar 12. At the same side of the machine as the blower and the spout, a brace 86 is provided which extends from the bar 85 16 to the turntable and may be an extension of the upper beam of the main frame.

To support the blast spout over the machine, we provide a prop consisting of a straight shank 87 which may be secured to 90 brackets bolted to the top of the main frame and has its upper end turned laterally, as shown at 88, a stirrup or rest 89 being secured upon and carried by the free end of the said laterally turned portion. This stirrup 95 89 is adapted to fit partly around the section 77 of the spout when the spout is arranged to project forwardly over the machine, as shown in Figs. 2 and 3, in which case it will be noted that the sections are separated and are tied side by side with a rope 90. It will be seen that in this described and illustrated position of the prop, the lateral arm 88 projects rearwardly over the machine and the spout is arranged in disassembled, compact form, so that the machine may be driven over a road or may be transported, while economizing space. If it be desired to move 100 105

the machine over a road without disconnecting the sections of the spout or blast pipe, the prop 87 is turned so that the arm 88 will project forwardly and the stirrup will then be properly located to engage under the outer section of the pipe and support the same, it being thus seen that by merely reversing the position of the prop the point of support may be disposed at either side of the joint flanges 79, 83, and the spout firmly held whether the sections be coupled or uncoupled.

To support the spout in its working position, we provide a mast 91 which has its lower end, in the illustrated arrangement, resting upon a base block 92 secured rigidly upon the rear bar 16, and it is held against lateral displacement by a staple or ring 93 which is fixed upon the side of the brace 86. The arrangement shown permits the mast to rotate about its own axis if necessary. The mast is provided intermediate its ends with a lateral bend or off-set portion 94 adapted to fit around the spout when the spout is projecting over the machine. At the upper end of the mast a hook 95 is pivotally mounted to carry the pulley block 96 over which the hoisting cable 97 runs, and the base block 92 and the ring 93 are so disposed that the upper end of the mast will be brought into the vertical plane of the turntable 76 and alined therewith, the hook 95 being thus permitted to turn with the spout without causing entanglement of the hoisting cable. The end of the cable 97 is secured to a windlass or winding shaft 98 mounted upon the mast in the usual manner. This mast, when the machine is to be transported, is secured against one of the side bars 9, as shown in Fig. 2, so that it will be out of the way and yet will not be apt to be lost. The mast may be easily mounted, when the machine is to be set up for use, by a single operator, inasmuch as all that needs to be done is to engage the mast upon the base block and fit the ring or other retaining member 93 in place. The cable 97 carries a block and hook which is then engaged with the eye 80 upon the spout, after which a slight winding of the cable will lift the spout out of the stirrup 89 and permit it to be swung to the operating position. The bend or offset 94 in the mast permits the blower to be located closer to the central line of the machine than has been previously done without interference between the mast and the blower spout. By winding the cable 97, the spout will be lifted from the support 87 and then may be swung easily to any desired position, moving through an arc of 325° before striking the mast, and the mast may be moved in or out of position while the spout is resting on the

prop 87. By setting the blower in toward the center of the machine, we not only reduce the width of the machine but also avoid interference between the blower and the rear wheel which may track with the front wheel.

Upon the blower shaft, we secure a spiral feeder 100 which leads into the blower and overcomes the choking which would otherwise be caused by the blower shaft extending across the path of the outgoing material.

Having thus described the invention, we claim:

1. A corn-husking machine comprising a frame, working elements mounted within the frame, a blower at the rear end of the frame, a blast pipe extending from the blower and adapted to project over the frame, said blast pipe comprising a plurality of sections and means for securing the sections together, and a prop mounted upon the frame and having a laterally extending upper arm adapted to support the spout, the prop being reversible to support the spout when the sections thereof are disconnected or when the sections are in alinement.

2. In a corn-husking machine, the combination of a frame, an extension at the rear end of said frame disposed laterally beyond the adjacent side thereof, a brace extending from the lower part of said extension upwardly to the frame, a blower mounted upon the said extension, a spout leading from the blower, a mast mounted on the frame at the side of the extension and having a lateral bend to accommodate the spout in a position extending longitudinally over the frame, the mast being rotatable about its own axis and means carried by the mast for supporting the spout in operative position.

3. In a corn-husking machine, the combination of a frame, a blower at the rear end of the frame, a blast pipe leading from the blower and adapted to extend forwardly therefrom over the frame, and a reversible prop on the frame near the front thereof and having a lateral arm to support the pipe whether the latter is wholly above the frame or projecting longitudinally beyond the same.

4. In a corn-husking machine, the combination of a frame, a blower at the rear end of the frame, a blast pipe leading from the blower and adapted to extend forward over the frame, a mast rotatably mounted on the frame and having an offset to receive the pipe when the latter extends over the frame, and means carried by the mast for raising and supporting the pipe.

In testimony whereof we affix our signatures.

THEODORE H. OPPENHEIM. [L. S.]
BERNARD SELHORST. [L. S.]
